[57] CLAIM

The ornamental design for a detachable stroller tray, as shown and described.

DESCRIPTION

FIG. 1 is a top and side perspective view of a detachable stroller tray showing my new design. Portions of the strap shown broken away indicate indeterminate length and for convenience of illustration;

FIG. 2 is a top plan view thereof; and,

FIG. 3 is a bottom perspective view thereof.

FIG. 1

FIG. 3
